Inventor:

Thomas A. Ryan

UNITED STATES PATENT OFFICE.

THOMAS A. RYAN, OF YONKERS, NEW YORK.

TYPEWRITING MACHINE.

Application filed June 23, 1921. Serial No. 479,977.

To all whom it may concern:

Be it known that I, THOMAS A. RYAN, a citizen of the United States, residing in the city of Yonkers, county of Westchester, 5 State of New York, have invented new and useful Improvements in Typewriting Machines, of which the following is a specification.

This invention relates to the elimination of 10 the clicking noise made by the type striking against the paper, common in most key operated machines.

The useful, new, and novel construction of the machine, will be further disclosed in 15 this specification and the accompanying drawings.

Most of the parts are in duplicate, a group of similar parts being combined at each side, but treated in the description as one to 20 simplify matters, though what parts are in duplicate is readily understood.

Fig. 1 is a front elevation, having a part cut away to show the shift keys at the left end, the right side group of printing key 25 levers being shown assembled to a point beyond the key rod from which point the levers are angled to form the key-board. This part of the lever is shown only with half a dozen keys. A similar group of key-levers would 30 be assembled on the other side, but are not shown on the drawings. The spacing-bar is shown in three sections broken away at the ends and center. The balance of the operating parts are shown in plan view 35 in this figure. Fig. 2 is a side elevation of the machine, and operating parts. Fig. 3 is a cross-section on the line A through the type, drum, and projecting lever. Fig. 4 is a plan view of the drum crank-shaft, the 40 connecting levers, slidable stops, support-rod and actuating springs. Fig. 5 is a front elevation of a spring actuated U-shaped bar, and the normal holding bar. Fig. 6 is a 45 side elevation of same with a printing key lever. Fig. 7 is a front elevation of the connecting ends of the key holding bars and the co-acting upright lever. Fig. 8, is a side elevation of the supporting standard. Fig. 9, is a view of a section of the frame end that 50 supports the carriage rollers. Fig. 10 is a side view of the bell ringing mechanism.

The machine frame has formed in each upper side V-shaped recesses 2, in each side of which are set supporting rollers 3. A 55 corresponding supporting bracket having rollers is set between each end and the center,

but is not shown on the drawing. A carriage 4, has its ends 5 formed to correspond to the V-shaped frame. The carriage ends are connected by parallel rods 6 forming a 60 supporting track for the platen 7, which is supported on a shaft 8 revolving in the carriage ends. A rack 9 set parallel with the track has spaced teeth engaged by the spring 10¹ actuating the escapement lever 10, 65 which is pivoted to a member 11 having its ends formed to slidably engage a supporting standard 17, and has a rod 12 set on its face to which is movably secured one end of a lever 13, the other end of which is pivoted to the lugs 14 of the operating plunger 15 which is set slidably on a supporting rod 16 projecting from a supporting standard 17 and is encased in a spiral spring 18. The operating plunger is held to position by its 70 end 15¹ sliding between the uprights 19³ and 19⁴ of the projecting lever 19 which has pivoted near the top an arm 20 having a T-shaped head 20¹ which stands in a 75 T-shaped recess 21 extending around the drum when the type are assembled and formed by the recess 22¹ cut in each type 22. The type drum 23 has spaced guide lugs 23¹ extending around its outer edge, which are engaged by the guide end 19¹. To 80 the drum supporting standards 24 and 25 the crank-shaft 26 is journaled. And to each offset of the crank-shaft is journaled an end of a lever 27 and to the other end of each lever is pivoted a slidable stop 28, mounted 85 on a rod 29, and actuated by a spring 30. A rocking member 31 is pivoted at 19² to the lever 19, and has opposite arms 31¹ which operatively bear against the crank-shaft, and arms 31² having slots 31³ which are slightly 90 connected to the ends of a co-operating key-bar 32 which co-operates with the key levers and has arms which are pivoted to the key lever pivot 33. The key levers 34 are assembled in duplicate groups on either 95 side in close formation to beyond the key-rod, then they are angled to form the key-board. Each key lever is formed and spaced in a group so that the character designated on the key struck is in the printing range 100 when the key head 34¹ intercepts the drum stop 28.

Each key lever is formed adjacent to the key-rod 32 and supporting rod 29 into a T head 34¹ which forms when the key levers 110 are assembled longitudinal recesses 35 and 36. The slidable drum stop 28 travels

in the recess 35, and the forward end of the key lever T 34¹ rests in the range of travel of the stop 28 when a key is struck. The key levers are supported in the normal position by the universal-bar 32 which has its right angled ends pivoted to the bar 33, and its other opposed ends mounted slidably two ways in the slots 31² of the oscillator 31, and moves down when a key is struck 5 but is replaced by a U-shaped supporting bar 37 having its ends pivoted to the frame, and resting against the key-bar arm 32¹ adapted to hold the bar 37 from the recess 36 until a key is struck carrying the universal-bar 32 and the arm 32¹ away from the U-bar when it is drawn into the recess 36 by the springs 38 and 39. When the supporting universal-bar 32 moves down away from under the key levers, bar 37 supports all but the struck key. When the key is released a reverse action of the arm 32¹ forces the bar 37 from the recess 36 so the next key is free when struck. When each type prints more than one character, 15 the type is raised and lowered to the printing range by supporting the parts on a movable base 40, having angled ends 41, to which are secured pins 42, that are slidable in the frame holes 43, of the frame base 30 44, and are cushioned by the washer 45. The movable base is operated by the shift keys 49 and 50 having levers 51 that extend back beyond the pivot and are angled to the center of the portable base. The range 35 of the type and keys is limited by the regulating slots in which the keys slide, and may be locked to maintain the desired characters in the printing range by turning the locking levers 52 and 53 which are pivoted 40 to the frame above regulating slots cut to a depth equal to the width of the part of the key-lever engaging the slots, so that when the locking levers are turned across the slots the movable base is locked in its 45 raised position holding the desired type in the printing range. The standard 46 supports the slide member 11. A striker 47 is pivoted to the frame and has one end operatively resting against the plunger 15, 50 swinging the striker when a key is struck and striking an adjustable alarm bell 48 mounted on the carriage. A spacing-bar 54 having spaced supporting arms 55 projecting back is aligned with the key levers and 55 is journaled on the rod 33 and a center arm 56 operatively engaging the plunger 15 and the escapement pawl 10 controls the movement of the carriage.

The machine operates as follows. When 60 a key 34 is struck it produces a simultaneous action of the key-bar 32, the rocking member 31, crank-shaft 26, drum 23, lever 27 and the stop 28, which rotates the drum 23 until the stop 28 sliding on the bar 29 compresses the spring 30 and is intercepted

by the key-lever stop 34¹ which is drawn into the recess 35. The type printing the character designated on the key is held in the printing range as the power in the struck key is transferred to the projecting lever 19, producing a simultaneous action of the lever 19, plunger 15, lever 13, slide member 11, and the escapement lever 10. This action forces the projecting lever 19 forward, setting the guide end 19¹ between two of the guide lugs 23¹ holding the drum 23 in position as the arm 20 projects a type 70 75 22 printing the character on the paper held on the platen 7, forces back the plunger 15 sliding on the rod 16, projecting from the standard 17, and stores the energy in spring 18. The lever 13 of the plunger 15 imparts a lateral movement to the slidable member 11 which sets the escapement lever 10 in an advanced tooth in the rack 9. 80 When the struck key 34 is released the stored energy in the springs 18 and 30 automatically returns all parts to normal position, and advances the carriage one letter space. When the carriage reaches the end 85 of a line, it is free to return when the spacing bar is held.

Having thus described my invention what I claim as new is:

1. The combination in a typewriting machine, of a movable carriage, a platen, a toothed rack, said rack operatively engaged by an escapement pawl pivoted to a slidably mounted reciprocating member, said member hinged to a spring actuated plunger, said plunger actuated by a universal-bar and printing keys. 95

2. The combination in a typewriting machine, of type operatively assembled in a rotatable drum, said drum mounted on a crank-shaft, said crank-shaft operatively connected to opposed spring actuated gages, said gages slidably mounted to have their travel intercepted when a key is struck in a range of keys, with means to print the character designated on the struck key. 105 110

3. The combination in a typewriting machine, of type, said type carried in a rotatably mounted drum, said drum mounted on a crank-shaft, opposed spring actuated slidably mounted gages, an oscillator, said oscillator having opposed upright arms operatively engaging said crank-shaft, and having opposed arms operatively formed into a universal bar, said universal bar actuated by printing keys, with means to print the character designated on a key. 115 120

4. The combination in a typewriting machine, of type, said type having means to be successively operatively engaged when assembled in a rotatable drum, said drum mounted on a crank-shaft and having spaced projecting lugs on its periphery, and key controlled gages, an oscillator, said oscillator mounted on an upright hinged 125 130

lever, said lever having means to operatively engage said type and said drum, a universal bar, printing keys, with means to successively bring within the printing range, project, and print, and return to said drum the type designated on a key.

5. The combination in a typewriting machine, of type, a rotatable drum adapted to carry said type, a crank-shaft adapted to 10 rotate said drum, an oscillator adapted to operate said crank-shaft, gages adapted to control said drum, a lever adapted to engage said type, a universal bar, and printing keys, with means to print the character 15 designated on a struck key.

6. The combination in a typewriting machine, of printing-keys having levers formed into opposed recesses, said recesses forming longitudinal recesses when said 20 keys are assembled, spring actuated gages slidably mounted to travel in said recess until operatively engaged by a key to control the rotation of a drum, a spring actuated holding bar, said holding bar 25 adapted to engage said recess when a key is struck to hold said keys aligned, with means to print the character designated on a struck key.

7. In a key machine having a platen, the 30 combination of a rotatable drum, type formed to successively operatively engage a co-operative form on a member adapted

to project and return said type to said drum, with means to print the type designated on a struck key.

35

8. In a type-writer having a movable carriage, the combination of a rotatable drum adapted to carry type and mounted on a crank-shaft, a member adapted to project and return said type, an oscillator combined with a universal bar and printing keys, said parts supported on a movable base mounted on a machine frame, with shift-keys having locking means, and adapted to set various characters on said type in the printing 45 range.

9. In a type-writing machine having a movable carriage and an adjustable alarm bell, combined with a rotatable drum mounted on a crank-shaft and carrying type, means operable by printing-keys to print said type, and operate a striker adapted to strike said bell when it comes within range, with a spacing-bar adapted to move said carriage in letter spacing direction.
